UNITED STATES PATENT OFFICE

105,636

DESIGN FOR A SWEATER ENSEMBLE

Sol Kurtz, New York, N. Y.

Application May 4, 1937, Serial No. 69,156

Term of patent 3½ years

To all whom it may concern:

Be it known that I, Sol Kurtz, a citizen of the United States of America, residing in city of New York, county of New York, and State of New York, have invented a new, original, and ornamental Design for a Sweater Ensemble, of which the following is a specification, reference being had to the accompanying drawing, forming part thereof,

Fig. 1 is a front view of a sweater ensemble showing my new design.

The back of the coat section is conventionally plain, while the back of the sweater section is identical with the front.

The characteristic feature of my design resides in the sleeveless jacket member of the ensemble which jacket is decorated as shown.

I claim:

The ornamental design for a sweater ensemble substantially as shown and described.

SOL KURTZ.
